UNITED STATES PATENT OFFICE.

FIDELE F. RICHARD, OF MONCTON, NEW BRUNSWICK, CANADA.

VALVE-GRINDER.

1,400,000.

Specification of Letters Patent. Patented Dec. 13, 1921.

Application filed February 9, 1921. Serial No. 443,570.

To all whom it may concern:

Be it known that I, FIDELE F. RICHARD, a subject of the King of England, residing at Moncton, in the Province of New Brunswick and Dominion of Canada, have invented a new and useful Valve-Grinder, whereof the following is a specification.

The device forming the subject matter of this application is adapted to be used for 10 grinding the valves of an internal combustion engine.

The invention aims to provide novel means for imparting rotation to a shaft which, in turn, transmits rotation to the 15 valve, novel means being provided for moving the shaft endwise, and novel means being supplied for supporting the shaft for rotation, and for adjusting the position of the shaft with respect to the valves which 20 are to be ground.

It is within the province of the disclosure to improve generally and to enhance the utility of devices of that type to which the invention appertains.

25 I do not bind myself to the specific form shown in the drawings and hereinafter described, since, within the scope of what is claimed, a mechanic may make such changes as his skill may dictate, without departing 30 from the spirit of the invention.

In the drawings:—Figure 1 shows in side elevation, a device constructed in accordance with the invention, mounted on an engine; Fig. 2 is a top plan of the structure 35 shown in Fig. 1; Fig. 3 is a section on the line 3—3 of Fig. 2; Fig. 4 is a top plan of the casing, the lid being removed; Fig. 5 is a section on the line 5—5 of Fig. 3; Fig. 6 is a section on the line 6—6 of Fig. 3; Fig. 40 7 is a section on the line 7—7 of Fig. 3; Fig. 8 is a section on the line 8—8 of Fig. 1.

The device forming the subject matter of this application, includes a support comprising a base plate 1 carrying a split clamping sleeve 2 provided with ears 3 connected by a screw 4. The base plate 1 has an opening 5 adapted to receive a securing element 6 whereby the base plate may be held on the cylinder block 7 of an internal combustion 45 engine. It may be convenient to hold the base plate 1 on the cylinder block 7 by means of one of the stud bolts which, being received in the openings 8, ordinarily hold the cylinder head on the block 7. A stand 50 ard in the form of a screw 9 is threaded into the sleeve 2 and is provided at its upper end

with a head 10 carrying a set screw 11. An arm 12 is adjustable longitudinally in the head 10 and is offset at one end, as shown at 14.

60 The offset end 14 of the arm 12 extends beneath a cylindrical casing 15 including a removable lid 16, the casing having a reduced neck 17 received between jaws 18 on the part 14 of the arm 12, the jaws being constrained by a screw 19 to grip the neck 17 of the casing. A tubular shaft 20 is journaled at one end in the neck 17 of the casing, the other end 21 of the shaft being reduced and being journaled in a boss 22 on 70 the lid 16. The shaft 20 includes a threaded part 23, whereon a disk 24 is held, the disk having a peripheral groove 25. A lever 26 is fulcrumed intermediate its ends, as at 27, on the casing 15. That portion of 75 the lever 26 which extends into the casing 15 carries a fork 28, the members of which are provided with pins 29 whereon rollers 30 are journaled, the pins and the rollers constituting projections received in the 80 groove 25 of the disk 24.

A coiled spring 31 is disposed about the shaft 20, one end of the spring being secured to the shaft, as denoted by the numeral 32. To the other end of the spring 85 31, a flexible element, such as a bit of chain, is secured, the chain being denoted by the numeral 33, and extending outwardly through an opening 34 in the casing 15. The part 33 terminates in an enlargement or 90 ring 35 of such a size that it cannot be pulled inwardly through the opening 35.

A drum 36 is formed on the shaft 20 and receives a flexible operating member 37, which may be a strap. The inner end of 95 the operating member 37 is secured at 38 to the shaft 20, the outer end of the operating member being extended through any one of a number of openings 39 in the casing 15. Externally of the casing 15, the 100 operating member 37 carries a handle 40.

A tool holder, in the form of a rod 41, is adjustable longitudinally in the shaft 20 and is held in adjusted positions by a set screw 42 threaded into the shaft. A pivot 105 element 44 in the lower end of the member 41 carries a blade 43 or other tool, adapted to engage one of the valves 45 of the engine.

In operation, the shaft 20 and the tool holder 41 are rotated in one direction by a 110 pull exerted on the operating member 37 by way of the handle 40. The spring 31 rotates

the shaft 20 and the holder 41 in an opposite direction. Clearly, the construction is such that the engine valve will be rotated first in one direction and then in an opposite direction. The shaft 20 may be moved endwise through the medium of the lever 26. The lever 26 constitutes means whereby any desired pressure may be put on the valve and, further, since the shaft 20 can be moved endwise by the lever 26, the valve may be lifted at any time, to permit grinding paste to be placed under the valve. The tool holder 41 may be adjusted endwise in the shaft 20, so that the tool 43 will engage the valve. The flexible connection 33 between the spring 31 and the casing 15 prevents the spring from being distorted when the shaft 20 is moved longitudinally by the lever 26. The set screw 11 may be loosened, thereby permitting the arm 12 to be moved lengthwise in the head 10, to the end that the tool 43 may be engaged with any of the valves 45. The arm 12 may be raised and lowered by threading the screw 9 upwardly or downwardly in the sleeve 2. After the screw 9 has assumed the desired position, it may be held against rotation by tightening up the screw 4. Since the screw 9 can rotate in the sleeve 2, the arm 12 and the casing 15 may be swung to one side, away from the valves.

I claim:—

1. A valve grinder comprising a support; a tool-carrying shaft journaled in the support and movable longitudinally therein; means under the control of an operator for rotating the shaft in one direction; spring means for rotating the shaft in an opposite direction; and means under the control of an operator for moving the shaft longitudinally.
2. A valve grinder comprising a support; a lever fulcrumed thereon; a tool-carrying shaft journaled in the support and in the lever and movable longitudinally in the support; spring means for rotating the shaft in one direction; and means under the control of an operator for rotating the shaft in an opposite direction.
3. A valve grinder comprising a support; a shaft journaled in the support and movable longitudinally therein; a flexible operating member wound about the shaft; a helical spring about the shaft and connected at its inner end to the shaft; means for moving the

shaft longitudinally; and a flexible connection between the outer end of the spring and the support and preventing a distortion of the spring when the shaft is moved longitudinally.

4. In a device of the class described, a base; means for securing the base to an engine; a standard adjustable longitudinally on the base; means for holding the standard in adjusted positions with respect to the base; an arm longitudinally adjustable in the standard, transversely of the standard; means for holding the arm in adjusted positions with respect to the standard; a rotatable valve-engaging member journaled on the arm; and means for rotating said member.

5. In a device of the class described, a base; means for securing the base to an engine; a standard mounted for rotation and for longitudinal movement on the base; means for holding the standard in adjusted positions with respect to the base; an arm adjustable longitudinally in the standard, transversely of the standard; means for holding the arm in adjusted positions with respect to the standard; and a rotatable valve-engaging member journaled in the arm.

6. A valve grinder comprising a casing; a tubular shaft journaled in the casing and longitudinally slidably therein; a lever fulcrumed on the casing, the shaft being journaled on the lever, and the lever constituting means for imparting longitudinal movement to the shaft; a tool holder adjustable longitudinally in the shaft; means for retaining the holder in adjusted position longitudinally of the shaft; means under the control of an operator for rotating the shaft in one direction; spring means for rotating the shaft in an opposite direction; a support wherein the casing is rotatably held for adjustment, thereby to adjust the position of the lever with respect to an operator; and means for holding the casing against rotation in the support.

In testimony that I claim the foregoing as my own, I have hereto affixed my signature in the presence of two witnesses.
